UNITED STATES PATENT OFFICE.

JACOB L. KLEINMAN, OF NEW YORK, N. Y.

PENCIL.

Application filed January 23, 1921. Serial No. 440,847.

To all whom it may concern:

Be it known that I, JACOB L. KLEINMAN, a citizen of the United States, and resident of the city of New York, in the county of New York and State of New York, have invented a certain new and useful Pencil, of which the following is a specification.

This invention relates to pencils, and particularly to a type provided with a lead magazine and mechanism for automatically receiving the lead directly from the magazine and feeding it forwardly as it wears away during use.

The principal object of my invention is to provide a simplified, inexpensive, conveniently and economically manufacturable, conveniently utilizable, efficiently operating, strong, durable, and improved pencil of this type.

Another object is to provide a pencil of this type, wherein the lead may be at all times propelled inwardly, as well as fed forwardly, by the manipulation of the mechanism.

Other objects and advantages will herein-after appear.

In the accompanying drawings,—

Fig. 1 is a general sectional elevation of the pencil.

Figs. 2 and 3 are respectively a plan and elevation of a detail of the pencil mechanism.

Figs. 4, 5, and 6 show cross-sectional plan views of the said detail on the lines 4—4, 5—5 and 5—5 respectively in Fig. 1 with the parts in different positions.

Fig. 7 shows an elevation of a lead which is specially adapted for use with this pencil.

The holder 1 of the pencil is tubular and tapers at 2 toward the writing end 3, whereat it terminates in a straight tubular portion, the interior side of which is parallel to and fits the lead. In the upper part of the holder 1 is located a magazine 4, normally loaded with supply leads 5, which magazine comprises a tubular shell that fits against the interior side of the holder 1, wherein it is rotatably mounted by means of an indentation 6 in the holder fitting into a similar annular indentation 7 in the shell 4. The bottom 8 of the magazine 4 is thickened and is provided with a central opening 9, toward which the floor 10 of the magazine tapers downwardly

and its exterior side 11 tapers upwardly. Said magazine-shell projects above the upper extremity 12 of the holder, and a rubber plug 13 threads into the upper end of the shell 4, to effectively bottle up the leads 5 and to serve the purpose of an eraser during writing. A cap 14 slips over the projecting end 15 of the magazine shell 4, and it embraces the end 15 sufficiently firmly so that when the cap is rotated the magazine is carried around therewith and rotates within the holder 1.

To the bottom 8 of the magazine 4 are secured two guide-rods 16, 17 that are parallel to each other and project therefrom toward the writing end of the holder. Said rods pass through respective guide openings 18, 19 of a carriage 20 Figs. 1, 2, 3, that is provided with a threaded periphery which is in engagement with the tapped interior side 21 of the holder 1, whereby as the magazine 4 is rotated, by means of turning the cap 14, said guide rods are carried around therewith and the carriage 20 is in turn rotated and caused to thread forwardly and backwardly, according to the direction of rotation of the cap 14, in which manner the carriage may be thus advanced toward the writing end of the pencil and retracted therefrom. The carriage 20 is provided with a central opening 22, adapted to let the lead pass therethrough, and a transverse notch 23, wherein there are located a pair of springs 24, 25 that are wound around the rod 16, with their extremities 26 bearing against the upright interior side 27 of said notch and their ends 28 normally pressing against the rods 17 in such manner that their arms 29 are in the path of the axis of the carriage opening 22. When the carriage 20 is fully retracted to a position adjacent the magazine-bottom 8, a cam 30 formed upon the rod 17 bears against the springs 24, 25 and thereby forces their arms 29 away from the path of the opening 22, and when the carriage is advanced to the end of the holder 1, a cam 31 bears against the arm 29 and causes it to be held away from the path of the opening 22. When the carriage 20 clears the cams 30, 31 the springs 24, 25 fall back to their above mentioned normal position.

When it is desired to use the pencil, the

22

cap 14 may be slipped off and the rubber 13 unthreaded, and the magazine 4 may be then loaded with the leads 5 and said rubber and cap restored in place. The carriage 20 may 5 be then retracted fully by turning of the cap 14, whereupon it will assume a position adjacent to the magazine-bottom 8 and the cam 30 will act to repel the springs 24, 25 to clear the carriage opening 22, as shown in 10 Fig. 6. Thereupon one of the leads 5^a will pass through the opening 9 of the magazine floor 10 and will fall by its gravity through the carriage opening 22 until its sharp end 5^b will strike the writing terminal 3, which will arrest its fall, due to the bore of the terminal being very slightly smaller than the diameter of the lead. The carriage 20 may be then advanced, and the springs 24, 25 caused to clear the cam 30 15 20 and to fall back in their released state, whereupon the spring 25 will press the end of the lead 5^a against the notch-side 27 as shown in Fig. 5, and thereby secure the lead to the carriage, and the spring 24 will fall to the rear of this lead-terminal, as shown in Fig. 4, so that as the carriage is advanced further it will grip the lead and feed it forwardly through the writing terminal 3 to theretofore provide the pencil writing-point. 25 30 And as the pencil point wears away during the use the lead may be fed forwardly or drawn back for adjustment of the point by advancing and retracting of the carriage, by means of merely turning the cap 14 in opposite directions. In the manipulation of 35 the pencil the spring 25 holds the lead in place and the spring 24 insures against any accidental longitudinal displacement of the lead during the writing. The elongated extremity 3 of the holder, the bore of which 40 fits the lead serves to prevent any possible accidental breakage of the lead laterally, at any point between the extremity 3 and the carriage 20. When the carriage is advanced 45 to the extreme end of its stroke, adjacent the end 2 of the holder, the cam 31 presses the spring 25 away from the lead 5^a and thereby releases it, so that the butt end of the lead may be then withdrawn with the fingers and removed from the pencil. Preferably the lead is manufactured with a rear end 5^c of reduced diameter whereby as it wears down to the butt end the same will automatically fall through the writing end 55 3 of the holder, without requiring any pulling action thereon.

As the lead is thus used up another one of the leads, as the one shown at 5^d, makes its way through the opening 9 in the magazine floor and passes on toward the carriage 21. And in order to feed this lead on through the writing end of the pencil, it merely requires to retract the carriage 20 to the limit of its return stroke and to advance it forwardly whereupon the new lead is gripped by

the carriage and fed forwardly in the manner described previously. While the carriage is being retracted, preliminarily to securing the new lead thereto, the new lead is prevented from passing through the opening 22 by the abutment of its forward point against the spring 24. The slopes 32, 33 of the magazine 4 and carriage 20 serve to facilitate the direction of the leads into the openings 9, 22 and the slope 11 serves to return any lead back into the magazine that may accidentally fall back from the carriage 20 upon inverting of the pencil during the taking up of a new lead.

It will be evident that by means of this mechanism wherein the lead is secured to the carriage 20, the lead may be at any time propelled inwardly, by the mere back-rotation of the cap 14 in case the lead appears to have been fed out too far at the writing end.

Variations may be resorted to within the scope of the invention, and portions of the improvements may be used without others.

Having thus described my invention, I claim:

1. A pencil having the combination with a holder, of a relatively rotatable lead magazine, guiding means rotated by said magazine, a carriage mounted upon said guiding means and rotated thereby, means to advance and retract said carriage upon rotation, said magazine and carriage being adapted to permit the leads to pass singly from the magazine and through the carriage, means to secure one of the leads to said carriage when it is in retracted position, and means to bear upon the rear of the lead extremity when said carriage is advanced.

2. A pencil having the combination with a holder, of a relatively rotatable lead magazine, guiding means rotated by said magazine, a carriage mounted upon said guiding means and rotated thereby, means to advance and retract said carriage upon rotation, said magazine and carriage being adapted to permit the leads to pass singly from the magazine and through the carriage, means to secure one of the leads to said carriage when it is in retracted position, means to bear upon the rear of the lead extremity when said carriage is advanced, and means to release the lead when said carriage is in advanced position.

3. A pencil having the combination with a holder, of a relatively rotatable lead magazine, guiding means rotated by said magazine, a carriage mounted upon said guiding means and rotated thereby, means to advance and retract said carriage upon rotation, said magazine and carriage being adapted to permit the leads to pass singly from the magazine and through the carriage, means to secure one of the leads to said car-

riage when it is in retracted position, and said holder having an elongated tubular portion with a parallel bore adapted to fit against the lead.

- 5 4. A pencil having the combination with a holder, of a relatively rotatable lead magazine, guiding means rotated by said magazine, a carriage mounted upon said guiding means and rotated thereby, means to
- 10 advance and retract said carriage upon rotation, said magazine and carriage being adapted to permit the leads to pass singly from the magazine and through the carriage, means to secure one of the leads to
- 15 said carriage when it is in retracted position, and said holder having an elongated tubular terminal with a parallel bore adapted to fit against the lead.

5. A pencil having the combination with
20 a holder, of a relatively rotatable lead magazine, guiding means rotated by said magazine, a carriage mounted upon said guiding means and rotated thereby, means to advance and retract said carriage upon rotation, said magazine and carriage being
25 adapted to permit the leads to pass singly from the magazine and through the carriage, means to secure one of the leads to said carriage when it is in retracted position, means to release the lead when said carriage is in advanced position, and the lead having its rear terminal of a reduced diameter to permit withdrawal thereof upon its release.

35 6. A pencil having the combination with
a holder, of a lead magazine, a carriage in
said holder adapted to be advanced and re-
tracted, said magazine and carriage being
adapted to permit the leads to pass singly
40 from the magazine and through said car-
riage, means to secure the lead to the car-
riage when it is in retracted position, and
means on said carriage to bear at the rear
45 of the lead extremity as the carriage is ad-
vanced.

7. A pencil having the combination with
a holder, of a lead magazine, a carriage in
said holder adapted to be advanced and re-
tracted, said magazine and carriage being
50 adapted to permit the leads to pass singly
from the magazine and through said car-
riage, means to secure the lead to the car-
riage when it is in retracted position, means
on said carriage to bear at the rear of the
55 lead extremity as the carriage is advanced,
and means to release the lead when it is in
advanced position.

8. A pencil having the combination with a holder, of a lead magazine rotatable relatively thereto, a guide-rod secured to said magazine, a carriage slideable over said rod, said holder being in threaded engagement with said carriage to advance and retract it, said magazine and carriage having openings to permit the leads to pass singly from

the magazine and through the carriage, and a spring on said carriage for securing one of the leads thereto when it is in retracted position.

9. A pencil having the combination with
a holder, of a lead magazine rotatable rela-
tively thereto, a guide-rod secured to said
magazine, a carriage slidable over said rod,
said holder being in threaded engagement
with said carriage to advance and retract
it, said magazine and carriage having open-
ings to permit the leads to pass singly from
the magazine and through the carriage, a
spring on said carriage for securing one of
the leads thereto when it is in retracted posi-
tion, a cam on said rod to release said spring
to permit the lead to pass through said car-
riage when it is in retracted position, and
said spring securing the lead to said car-
riage when it is advanced from the cam. 35

10. A pencil having the combination with
a holder, of a lead magazine rotatable relatively thereto, a guide-rod secured to said magazine, a carriage slideable over said rod, said holder being in threaded engagement 90 with said carriage to advance and retract it, said magazine and carriage having openings to permit the leads to pass singly from the magazine and through the carriage, a spring on said carriage for securing 95 one of the leads thereto when it is in retracted position, a cam on said rod to release said spring to permit the lead to pass through said carriage when it is in retracted position, said spring securing the 100 lead to said carriage when it is advanced from the cam, and a spring bearing upon the rear of the lead extremity when said carriage is advanced.

11. A pencil having the combination with 105
a holder, of a lead magazine rotatable relatively thereto, a guide-rod secured to said magazine, a carriage slideable over said rod, said holder being in threaded engagement with said carriage to advance and retract 110 it, said magazine and carriage having openings to permit the leads to pass singly from the magazine and through the carriage, a spring on said carriage for securing one of the leads thereto when it is in retracted position, a cam on said rod to release said spring to permit the lead to pass through said carriage when it is in retracted position, said spring securing the lead to said carriage 115 when it is advanced from the cam, and another cam on said rod to release said spring for freeing the lead when said carriage is in advanced position. 120

12. A pencil having the combination with
a holder, of a lead magazine rotatable rela- 125
tively thereto, a guide-rod secured to said
magazine, a carriage slideable over said rod,
said holder being in threaded engagement
with said carriage to advance and retract
it, said magazine and carriage having open- 130

ings to permit the leads to pass singly from lease said springs and permit the leads to the magazine and through the carriage, a pass through said carriage when it is in re-
spring on said carriage for securing one tractored position.
of the leads thereto when it is in retracted. Signed at the city of New York, in the
5 position, a spring bearing upon the rear county of New York, and State of New
of the lead extremity when said carriage York, this 28th day of January, A. D. 1921.
is advanced, and a cam on said rod to re- JACOB L. KLEINMAN.
